PISTON

Filed March 12, 1923

Inventor:
Elmer C. Irons.
By H. G. Fletcher
Atty.

UNITED STATES PATENT OFFICE

ELMER C. LONG, OF DETROIT, MICHIGAN, ASSIGNOR, BY MESNE ASSIGNMENTS, TO SECURITY TRUST COMPANY, OF DETROIT, MICHIGAN, A CORPORATION OF MICHIGAN

PISTON

Application filed March 12, 1923. Serial No. 624,463.

The invention contained in this application is a furthering of the improvements and principles contained in my pending application for U. S. Letters Patent filed December 5 17, 1921, Serial No. 522,974, and my pending application Serial No. 607,660, filed on November 22, 1922, the primary object of this invention, however, having for its purpose the provision of means which extend from one 10 side of the skirt portion of the piston to adjacent separated portions which are oppositely disposed therefrom. The aforesaid means being peculiarly disposed are designed so as to tend to reduce the diameter of the 15 skirt portion of the piston when expanding forces are being given to the piston by the heated conditions contained within the cylinder of an internal combustion motor in which this improved piston is adapted to recipro- 20 cate.

Another object of the invention is to provide supporting webs of the piston with radiating fins or members.

Other and further objects will appear in 25 the specification and be specifically pointed out in the appended claims, reference being had to the accompanying drawings, exemplifying the invention, and in which:—

Figure 1 is a vertical section taken through 30 its improved piston on the line I—I of Fig. 2.

Figure 2 is a vertical section taken approximately on the line II—II of Fig. 1.

Figure 3 is an inverted view of Fig. 1 taken in the direction of the arrow 3.

Figure 4 is a horizontal section taken on the line IV—IV of Fig. 2.

With reference to the accompanying drawings, this improved piston is provided with a closed end 1 and an open end 2 and adjacent 40 the closed end 1 on the periphery of the piston is provided a series of packing ring recesses 3.

Depended from the closed end 1 within the piston are a series of reinforcing webs 4 and leading downwardly from each web and formed integral with opposite sides of the piston is a continuing web 5, said continuing webs on each side of the piston extending to and are formed integral with respective wrist 50 pin bearings 6.

As clearly shown in Figs. 1 and 2 a transverse annular slotting 7 is cut entirely through the thickness of the peripheral wall of the piston, said slotting extending nearly around the piston with the exception of the portion 55 8 on the back-slap-side 9 of the piston which is disposed at right angles to the wrist pin bearings 6, said slotting dividing the piston into a packing ring bearing portion 10 and a skirt portion 11. 60

The annular slotting 7 is disposed within the lowermost recess 12 for the reception of a packing ring 13.

Extending from the back-slap-side 9 of the piston is a pair of transversely disposed supporting webs 14, each of said webs being formed integral with the skirt portion of the piston and with one side of a respective wrist pin bearing 6, each of said webs extending from the skirt portion of the piston to respective wrist pin bearings at an angle of approximately 45 degrees, as designated at 15. Each of the webs 14 from their point of intersection with the wrist pin bearings is extended beneath its respective wrist pin bearings and are spaced apart from the wrist pin bearings, as shown at 16, said webs continuing in their transverse disposition and are integrally connected at 17 to opposite sides of the skirt portion of the piston. Each of the webs 14 70 75 80 is provided with a plurality of extending radiating fins 18.

From the disclosure of Figs. 1, 3 and 4 of the drawings, it is to be noted that the wrist pin bearings 6 while being depended within the skirt portion 11 of the piston, are also suspended from the closed end 1, such suspended construction providing for the wrist pin bearings being free from engagement with the skirt portion 11. 90

A slot 19 is extended from the open end 2 of the piston to the annular slot 7, said slot being formed entirely through the thickness of the peripheral wall of the skirt portion 11.

In the operation of this improved piston when the same becomes heated by virtue of the explosions occurring within the cylinder of an internal combustion motor, expansion will consequently be given to the piston, and inasmuch as the closed end 1 on account of be- 95 100

ing in direct contact with the explosive heat, it is only natural that the maximum amount of heat will be received and contained in said closed end, but on account of the annular slotting 7 which divides the skirt portion 11 5 from said closed end 1, the maximum amount of heat from the closed end 1 can not be transferred to the skirt portion, and consequently the extreme heated conditions caused by the explosions in the cylinder will not be given to 10 the skirt portion.

The skirt portion, however, will eventually become heated somewhat both from sliding contact of the skirt portion with the cylinder wall and from the heat of the cylinder, and 15 the same will tend to expand in diameter, but on account of the peculiar disposition of the supporting webs 14 which extend from the back-slap-side 9 of the piston to the adjacent separated parts 20 of the skirt portion provided by the slot 19, said webs will not permit the portions 20 to expand or move too far outwardly on account of said portions 20 being anchored by the webs 14, and on account 20 of the angular portions 15 being disposed as they are, the extending portions of the webs 14 which engage the portions 20 of the skirt will tend to move inwardly towards each other as indicated by the lines 21 in Fig. 4 in which 25 the portions 20 of the skirt portion will move towards closing the lengthwise arranged slot 19.

From the aforesaid description of this improved invention, it is readily seen that the 30 peripheral wall of the skirt portion of the piston is prevented from too tightly engaging the cylinder wall during extreme heated conditions of the cylinder.

For preventing horizontal displacement of the wrist pin 22 within the bearings 6 a set 35 screw 23 is threadingly engaged within a boss 24 which is formed on one of said bearings, said boss at its depending end being provided with a pair of notches 25 through which a cotter-key 26 is engaged as it is being mounted in the opening 27 which is provided transversely through the outer end of the set screw 23. The set screw 23 is adapted to engage the wrist pin 22.

50 What I claim is:—

1. A piston comprising a head and a skirt and pin bosses, said skirt being provided with a slit which extends from a point near the head to the open end of the piston, said slit 55 providing adjacent disconnected portions on one side of the skirt, and cooperating members extending from one side of a respective pin boss to opposite sides of the skirt and being free from engagement with the lower 60 sides of the pin bosses.

2. A piston open at one end and having a slot extending from the open end towards the closed end thereof, and means arranged within the piston and extending to the parts provided by the slot thereof whereby when the

piston is subjected to heat the expansive forces thereof will contract the diameter of the skirt portion of the piston.

3. A piston solid at one end and having the skirt portion thereof partially separated from the solid end, said skirt portion being provided with a slot extending from the open end so as to provide flexibility thereto, and means provided on said piston whereby said skirt portion tends to draw inwardly from the expanding portion of the piston. 75

4. A piston solid at one end and having the skirt portion thereof partially separated from the solid end, said skirt portion being slotted so as to provide flexibility thereof, a wrist pin bearing portion depended from said solid end, and means extending from said bearing to said skirt portion whereby when said wrist pin bearing is moved outwardly by expansion, the slotted portion of said skirt portion 80 will tend to move inwardly. 85

5. A piston open at one end and having its peripheral wall slotted from its open end so as to provide flexibility thereto, a rigid portion formed interiorly of the piston separated from its peripheral wall, and means connecting said rigid portion to said peripheral wall for tending to draw a portion of said peripheral wall inwardly. 90

6. A piston having a pair of wrist pin bearings, which are separated from the peripheral wall of the skirt portion of the piston, said skirt portion also being partially separated from the solid end of the piston and bearing a longitudinally extending slot cut entirely through its peripheral wall, and connecting means extending from each of said bearing portions to said skirt portion, said connecting means providing means for tending to close the slot of said skirt portion when the piston is subjected to expansion. 95 100 105

7. A piston having a pair of wrist pin bearings which are separated from the peripheral wall of the skirt portion of the piston, a slot cut entirely through the thickness of the peripheral wall of said skirt portion extending from the open end thereof, a pair of webs extending from one side of said skirt portion opposite to said slot, each of said webs being formed integral with a respective wrist pin bearing and extending to the adjacent disconnected portions provided by said slot. 110 115

8. A piston having a pair of wrist pin bearings which are separated from the peripheral wall of the skirt portion of the piston, a slot cut entirely through the thickness of the peripheral wall of said skirt portion extending from the open end thereof, a pair of webs extending from one side of said skirt portion opposite to said slot, each of said webs being formed integral with said skirt portion and a respective wrist pin bearing, said webs from their point of intersection with said wrist pin bearings extending beneath and away from the respective bearings with which they are 120 125 130

connected to respective adjacent disconnected portions of the skirt portion provided by said slot.

9. A piston having a pair of wrist pin bearings which are separated from the peripheral wall of the skirt portion of the piston, a slot cut entirely through the thickness of the peripheral wall of said skirt portion extending from the open end thereof, a pair of webs 10 extending from one side of said skirt portion opposite to said slot, each of said webs being formed integral with a respective wrist pin bearing and extending to the adjacent disconnected portions provided by said slot, each of 15 said webs being provided with a plurality of projections.

10. A piston closed at one end and open at its opposite end, said piston having a transverse slot partially separating the closed end 20 of the piston thereby providing a separated skirt portion to the piston, said skirt portion having a slot extending from its open end to said transverse slot, said slots being cut entirely through the thickness of the peripheral 25 wall of the piston, a pair of webs extending from one side of said skirt portion opposite to said slot, each of said webs being formed integral with a respective wrist pin bearing and extending to the adjacent disconnected 30 portions provided by said slot, each of said webs being provided with a plurality of projections.

11. A piston comprising a head and a skirt, said skirt being provided with a slit which 35 extends from a point near the head to the open end of the piston, said slit providing adjacent disconnected portions on one side of the skirt, a pair of wrist pin bearings, and a pair of webs each being connected to an adjacent 40 disconnected portion and to the opposite side of the skirt and to one side of said pin bosses.

12. A piston comprising a head and a skirt, said skirt being provided with a slit which 45 extends from a point near the head to the open end of the piston, said slit providing adjacent disconnected portions on one side of the skirt, means co-operable with said disconnected portions extending from the opposite side of the 50 skirt to each of the disconnected portions, and means forming a part on each of said extending means for determining the fulcrum point thereof.

13. A piston comprising a head and a skirt, 55 said skirt being provided with a slit which extends from a point near the head to the open end of the piston, said slit providing adjacent disconnected portions on one side of the skirt, and a web extending from the opposite 60 side of the skirt to each of the adjacent disconnected portions each being provided with a bended portion adjacent the side of the skirt which is opposite to said slit, said bended portions each providing a fulcrum to a respective 65 web.

14. A piston comprising a head and a skirt, said skirt being provided with a slit which extends from a point near the head to the open end of the piston, said slit providing adjacent disconnected portions on one side of the skirt, a pair of wrist pin bearings, and a web extending from the opposite side of the skirt to each of the adjacent disconnected portions each being provided with means for determining the fulcrum point thereof, said webs being arranged on a plane below said bearings. 70

15. A piston comprising a head and a skirt, said skirt being provided with a slit which extends from a point near the head to the open end of the piston, said slit providing adjacent disconnected portions on one side of the skirt, a pair of wrist pin bearings depended from said head, and a web extending from the opposite side of the skirt to each of the adjacent disconnected portions and to one side of each of said bearings, said webs being arranged on a plane below said bearings and free from engagement with the under sides of 80 said bearings, each of said webs having an angular portion. 85

16. A piston comprising a head and a skirt, the peripheral wall of the skirt adjacent the head being provided with a transverse slot, said skirt having a slit which extends from 90 said slot to the open end of the piston, said slot and said slit providing adjacent disconnected portions on one side of the skirt, a pair of wrist pin bearings depended from said head being free from engagement with said skirt, and means active on said adjacent disconnected portions towards preventing said portions from moving outwardly extending from said 95 portions to the opposite side of the skirt. 100

17. A piston having a head portion and a sleeve-like skirt portion, said skirt portion being separated from said head portion by an annularly extending non-conducting gap, said skirt portion being slotted longitudinally from one end to the other, a pair of pin bosses 110 located interiorly of said skirt portion, and supporting means for said skirt portion extending from one side of said pin bosses to said skirt portion. 115

18. A piston closed at one end, a longitudinally slotted sleeve-like one-piece skirt separated from said closed end, a pair of wrist pin bearings depended from said closed end within said skirt, and a web extending from each of said bearings to one side of said skirt, each of said webs having a part extending to the opposite side of the skirt beneath said bearings. 120

19. A piston for an internal combustion motor comprising a head and a skirt and pin bosses, and a web extending from each pin boss to the skirt having a plurality of projections thereon. 125
